UNITED STATES PATENT OFFICE.

JULIUS WELLNER, OF JERSEY CITY, NEW JERSEY.

TUNE-SHEET HOLDER.

SPECIFICATION forming part of Letters Patent No. 658,035, dated September 18, 1900.

Application filed April 9, 1900 Serial No. 12,056. (No model.)

To all whom it may concern:

Be it known that I, JULIUS WELLNER, a citizen of the United States, residing at Jersey City, in the county of Hudson and State of New Jersey, have invented certain new and useful Improvements in Tune-Sheet Holders; and I do hereby declare the following to be a full, clear, and exact description of the invention, such as will enable others skilled in the art to which it appertains to make and use the same, reference being had to the accompanying drawings, and to letters of reference marked thereon, which form part of this specification.

15 My invention relates to tune-sheet holders in mechanical musical instruments.

The object of my invention is to furnish a device that will receive, hold, and release the tune-sheet. To effect this, I have devised and 20 constructed a holder that has pivotal action which receives and retains the tune-sheet while operating the star-wheels. In this pivotal action of the support, which rests in the center hole furnished in all circular tune- 25 sheets, my invention differs from the tune-sheet holders known to date, generally consisting in a horizontal pin having spring action backward and forward. It can be readily understood that during the opening movement this oblique position of the support in the tune-sheet hole is a great advantage, inasmuch as the tune-sheet is compelled to slide down the slanting pin, not alone by reason 30 of the pointed nature of the end of such pin, but additionally on account of its being withdrawn by said pivotal action. My device is furthermore very simple in its construction and possesses the quality of not relying on any spring action to release the tune-sheet, 35 such spring-actuated holders in these cases at all events being somewhat expensive and not uniformly reliable, because the spring is liable after a certain period to lose its elasticity and must in consequence be replaced 40 by another.

45 My improved tune-sheet holder can be applied to all kinds of mechanical musical instruments whether the tune-sheet in such instruments be fed toward the star-wheels in a 50 vertical or a horizontal position.

In describing my improvement I shall call attention to the accompanying drawings,

wherein like letters of reference indicate corresponding parts in the different views.

Figure 1 shows a front view of my tune-sheet holder if said holder is considered as applied to an instrument having the tune-sheets fed in a vertical position. If in an instrument having the tune-sheets fed horizontally, it will be a top view. Fig. 2 is an end 60 or side view of the tune-sheet holder as shown in Fig. 1. Fig. 3 is similarly an end view of said holder as shown in Fig. 1, but with the comb, star-wheels, and auxiliary elements omitted in order to more clearly show my invented means. Fig. 4 is a sectional view of the same parts that are shown in Fig. 3 through a line X X in Fig. 1; and Fig. 5, with the same explanation holding good relative to the position of the tune-sheet holder in a 65 vertical or a horizontal instrument, as in Fig. 1, is a front or top view, as the case may be, of the seat that receives the tune-sheet holder or, more explicitly speaking, the pin forming part of the pivotal arm of the tune-sheet 70 holder.

In the said figures A indicates the tune-sheet; B, the comb; D, the series of star-wheels operating the comb-teeth.

E is a plate, to which is secured by screws 80 E' and E² the two bearings F' and F². Pivoted in these bearings is the bar H, having an arm H', which arm can be operated by any of the motive means that may be used in the instrument in which my tune-sheet holder is 85 applied. Forming an integral part of or inserted firmly in this pivoted bar H is a pin I, said pin I being tapered at the end, so as to furnish thereby a safe and immediate release for the tune-sheet. Affixed to the plate E or 90 to any means that has the pivoted bar H pivoted to it is a seat K, said seat secured to the plate E by screws J', J², and J³. The said seat K is furnished with a hole K', which hole is adapted to receive the pin I and is to that 95 effect slightly elliptically formed at its mouth, as seen in Fig. 5. It can now be seen very clearly that when, as shown in Fig. 3, the pivoted bar H is open, having been brought into such position by some motive power operating on the arm H', and the tune-sheet A has been moved upward in a vertical instrument and laterally in a horizontal instrument in the direction of the arrow Z and has reached

the point where the centrally-located hole of the tune-sheet is, opposite to the tapered point of the pin I, then the above-stated motive means operating on the arm H' will move 5 the bar H pivotally in the direction of the arrow Z², the tune-sheet A thus resting on the pin I and the pin I being inserted in the hole K' of the seat K, as seen in Figs. 2 and 4.

I do not of course strictly limit myself to 10 the nature or construction of several of the elements shown in the drawings—as, for instance, to the means supporting the pivoted bar H or the means called by me the “seat” receiving the pin I—inasmuch as more adequate means than these might easily be substituted without interfering with my inventive principle of a pivotal tune-sheet holder. 15

What I claim, and desire to secure protection for by Letters Patent, is—
20 1. In a mechanical musical instrument, sep-

arate tune-sheets operating the same, a pivoted tune-sheet holder having a pin fixed thereto, a hollow seat coöperating with said pin substantially as and for the purposes described.

25

2. In a mechanical musical instrument having separate tune-sheets for operating the same, the combination with a pivoted tune-sheet holder having a pin fixed thereto of a hollow seat with which the pin interlocks, so 30 that said pin lies longitudinally through the axis of its seat.

In testimony that I claim the foregoing I have hereunto set my hand this 29th day of March, A. D. 1900.

JULIUS WELLNER.
